SYSTEM OF CONTROL.

1,427,352.

Specification of Letters Patent. Patented Aug. 29, 1922.

Application filed November 28, 1919. Serial No. 341,017.

To all whom it may concern:

Be it known that we, WILLIAM G. BROOKS, a citizen of the United States, and a resident of Chicago, in the county of Cook and State 5 of Illinois, and LYNN G. RILEY, a citizen of the United States, and a resident of Wilkinsburg, in the county of Allegheny and State of Pennsylvania, have invented a new and useful Improvement in Systems of Control, of which the following is a specification.

Our invention relates to systems of control and it has special relation to railway control systems for a plurality of tandem-connected vehicles.

Under heavy-traffic conditions, it is desirable to operate trains, comprising two or more cars to be controlled by a single motor-man stationed at the front end of the train. 20 In case remote-control equipments are available for this purpose, such multiple-unit trains may readily be assembled without requiring the use of any main cables or train lines between cars. However, if it is desired to operate, in tandem, two cars employing the familiar "K" controllers for direct main-circuit operation, a total of approximately eighteen cables or train lines between vehicles is necessary to provide means for 25 effecting series-parallel control and reversing control from the one or the other of the outer ends of the two vehicles. Evidently, this arrangement is unduly expensive, inconvenient and bulky, and various schemes 30 have been proposed in the prior art, whereby the number and capacity of the necessary train lines for the purposes set forth have been reduced to a certain extent.

It is one object of our present invention 40 to provide a control system embodying a still greater reduction in the necessary number of interconnecting cables or train lines, whereby the desired normal functions of series-parallel and reversing control of the 45 motors upon the two vehicles may be obtained from either operating platform merely by the customary operation of the "K" controller and the accompanying reverser.

More specifically stated, it is one object 50 of our invention to provide a control system, installed upon two tandem-connected vehicles, whereby series-parallel control of

the driving motors may be effected by a single train-line conductor.

Another object of our invention is to provide a system of the above-indicated character wherein both series-parallel and reversing control may be attained through the use of three train-line conductors, two of which are of relatively small capacity, carrying only auxiliary-circuit current. 55 60

Other objects of our invention will become evident from the following detailed description taken in conjunction with the accompanying drawing, wherein

Figure 1 is a simplified diagrammatic view of a control system organized in accordance with the present invention; and

Fig. 2 is a complete diagrammatic view of the preferred form of our invention. 65 70

Referring to Fig. 1, the system here shown comprises a plurality of vehicles generally represented by the reference characters 1 and 2, the separation of the vehicles being denoted by the centrally located vertical dotted line. Upon the vehicle 1, a driving motor having a commutator-type armature A1 and a series field winding F1 is provided, together with a type "K" platform controller 3 which is completely shown in Fig. 2; a plurality of accelerating resistors 4 and 5; a main-circuit reversing switch 6 and an auxiliary switching device 7 comprising a portion of the reversing switch that is customarily associated with "K" controller drums. 75 80 85

The tandem-connected vehicle 2 contains similar power and controlling units; namely, a driving motor having a commutator-type armature A2 and a series field winding F2, a type "K" platform controller 8, accelerating resistors 9 and 10, main reverser 11 and auxiliary reversing switch 12. 90

For the sake of clearness, the reversing switches 6, 7, 11 and 12 are shown in full lines corresponding to forward operation of the left-hand vehicle 1, as indicated by the solid-line arrows; while the dotted connections of the reversing switches correspond to forward operation of the right-hand vehicle 2, as indicated by the dotted-line arrows. 95 100

The customary supply circuits Trolley and Ground are provided for operating the

vehicle, a single trolley connection and a pair of alternatively used ground connections being associated with each power unit. Energy is drawn through the trolley pole 5 mounted upon the leading vehicle in either case, although the trolley pole on the other vehicle may be left in its upper position of contact with the trolley wire, if desired, since no energy can be delivered thereby to 10 the system by reason of the corresponding "K" controller remaining in its "off" position.

Assuming that it is desired to effect forward operation corresponding to the vehicle 15 1, as indicated by the solid-line arrows pointing toward the left, the main reverser 6 and the auxiliary reversing switch 7 are thrown to the positions corresponding to the solid-line connections, while the "K" controller 3 is actuated to its first operative position to make the connections, indicated in 20 Fig. 1 by broken lines for the sake of simplicity, between various controller fingers.

In this initial operative position of the 25 "K" controller, therefore, a circuit is established from the Trolley through conductor 15, control fingers 16 and 17, which are bridged by a contact segment 18 of the controller, the entire accelerating resistor 4, 30 control fingers 19 and 20, which are bridged by contact segment 20a, conductor 21, co-operating contact members of the auxiliary reversing switch 7 and of the main reverser 6, field winding F1, other contact members 35 of the main reverser 6, armature A1, contact members of the auxiliary reversing switch 7, conductor 22, the entire accelerating resistor 5, control fingers 23 and 24, which are bridged by contact segment 25 of the controller 3, and conductor 26 to the rear end 40 of the vehicle 1.

The conductor 26 is joined, through a suitable jumper cable or train line 27, to a conductor 28 on the vehicle 2, whence circuit 45 is completed through contact members of the auxiliary reversing switch 12, armature A2, contact members of the main reverser 11, field winding F2, other contact members of the reverser 11, contact members of the auxiliary reversing switch 12 and conductor 29 to Ground.

The two power units, in this instance shown as comprising single driving motors, are thus connected in series relation with 55 the accelerating resistors 4 and 5 on the vehicle 1 across the supply-circuit conductors, to start the vehicles into operation.

It will be noted that only the resistors installed on vehicle 1 are employed in the motor connections, and the resistors 9 and 10 on the other vehicle are idle. By making the several resistors of sufficient current-carrying capacity to permit safe operation in connection with both sets of vehicle motors, that is, of approximately twice the nor-

mal capacity for one power unit, it will be appreciated that the necessary interconnections between the resistors on the two vehicles, which would otherwise be necessary to obtain the proper capacity of grid resistors, are obviated in the present case. In this way, a total of seven main cables between vehicles are entirely eliminated.

By actuating the controller 3 to its successive operative positions, as will be fully described in connection with Fig. 2, the accelerating resistors 4 and 5 are gradually cut out of circuit until full series relation of the driving motors is obtained. It will be understood that further operation of the "K" controller 3 serves to effect parallel operation of the driving motors, with the accelerating resistors 4 and 5 initially connected in circuit again, in accordance with a customary practice. Similarly, series-parallel control 85 of the two sets of motors from the other operating platform, upon which the "K" controller 8 is installed, may be obtained. It is deemed sufficient, for the purposes of the present specification, however, to describe, in addition to the series operation in the forward direction that corresponds to vehicle 1, only the parallel operation in the forward direction corresponding to the vehicle 2, since the remaining two operations 90 will be clear by analogy.

Assuming, therefore, that the motors are connected in parallel operation to be controlled from the "K" controller 8, in the first place, the reversing switches 11 and 12 100 will have been thrown to the position indicated by dotted lines, whereby the vehicle motors will operate in the reverse direction from that originally assumed, as indicated by the dotted-line arrows.

Under these conditions, a circuit is established from the Trolley through conductor 35 on the vehicle 2, control fingers 36 and 37, which are bridged by contact segment 38 of the controller 8, where the circuit divides, one branch including conductor 38a, co-operating contact members of the auxiliary reversing switch 12 and of the main reverser 11 in their reversed positions, field winding F2, contact members of the main reverser 11, armature A2, contact members 110 of the auxiliary reversing switch 12, conductor 39, the entire accelerating resistor 10, conductor 40, control fingers 41 and 42, which are bridged by contact segment 43 of the controller 8, and conductor 44 to Ground.

The other branch circuit from contact segment 38 includes control finger 45, a portion of the accelerating resistor 9, control fingers 46 and 47, which are bridged by contact segment 48 of the controller 8, conductors 49 and 28, jumper cable or train line 27, conductor 28 on vehicle 1, contact members of the auxiliary reversing switch 7, armature A1, contact members of the main

125

130

reverser 6 in the dotted-line or reverse position, field winding F1, other contact members of the main reverser 6, contact members of the auxiliary reversing switch 7 and conductor 50 to Ground.

The two motors are thus connected in parallel relation, the resistors 9 and 10 being partially and wholly included, respectively, in circuit with the respective motors across 10 the supply-circuit conductors, to produce balanced operation. It will be understood that, by further manipulation of the "K" controller 8, the accelerating resistors 9 and 10 may be gradually removed from circuit 15 to effect full parallel connection of the motors.

It will be evident, from the foregoing description, that series-parallel control of two sets of driving motors located on tandem- 20 connected vehicles may be obtained by control apparatus upon the operating platform at each end of the train through the use of a single jumper cable or train-line conductor. The remaining cables or train lines, that 25 would necessarily be employed if two of the customary prior-art systems should be interconnected, are eliminated, partially by the use of double-capacity resistors on the respective vehicles, only one set of resistors 30 being employed at a time, and partially through the use of the auxiliary reversing switches 7 and 12 and the employment of remote control for the main reversers 6 and 11, as subsequently described in detail.

Referring to Fig. 2, the complete operating system shown comprises all of the apparatus that is shown in Fig. 1, together with remote-control or master reversing switches 7a and 12a that are respectively 40 movable with the auxiliary reversing switches 7 and 12.

The following description of the complete circuits follows the method employed in connection with Fig. 1, since, as previously stated, a complete description of all possible operations of the system is not considered necessary by reason of the analogy obtaining between certain of such operations.

The "K" controller 3 is adapted to occupy a plurality of operative positions *a* to *e*, inclusive, corresponding to series operation of the driving motors, and positions *f* to *h*, inclusive, corresponding to parallel operation thereof.

55 The resistors 4 and 5 comprise a suitable number of sections, certain of which are connected in parallel relation, it being understood that, whereas the present arrangement of resistor sections is a preferred form, any other combination may be employed to obtain the desired results, provided the capacity of the resistors is sufficient to handle both sets of driving motors.

The main reverser 6 is of a familiar electrically-controlled, preferably pneumati-

cally-actuated, type, having the necessary main-circuit contact members for reversing the relative connections of the armature A1 and the field winding F1, together with actuating coils respectively designated as 70 "For.-1" and "Rev.-1" for actuating the reverser to the one or the other of its operative positions in accordance with the position occupied by the master reversing switch 7a. The other main reverser 11 is of 75 the same form, embodying actuating coils For.-2 and Rev.-2.

The controllers 8, 12 and 12a are duplicates of controllers 3, 7 and 7a, respectively, and need no further description here, it being 80 simply noted that the "K" controller 8 is adapted to occupy positions *a'* to *h'*, inclusive, corresponding to positions *a* to *h*, inclusive, of the other main controller 3.

Assuming that it is desired to effect series 85 operation of the motors in the forward direction corresponding to vehicle 1, the auxiliary reversing switch 7 and master reversing switch 7a are thrown, by their common actuating handle (not shown), into the forward position marked "For."

If, at this time, the main reverser 6 happens to occupy its reverse position, a circuit is established from the Trolley, through conductors 55 and 56, control fingers 57 and 58, which are bridged by contact segment 59 of the master reversing switch 7a, conductor 60, actuating coil For.-1 of the main reverser 6, and conductor 61, to Ground. In this way, the main reverser 6 is actuated to 100 its illustrated forward position. At the same time, a branch circuit is completed from conductor 60, through conductor 51, terminal board 87 on the vehicle 1, conductor 52 comprising a jumper cable between vehicles, terminal board 88 on the vehicle 2, conductor 53, actuating coil For.-2 of the main reverser 11 and conductor 54, to Ground. Consequently, the main reversers on both vehicles are concurrently actuated to the illustrated 105 positions corresponding to forward operation with respect to the vehicle 1.

It will be understood that, whenever the main reversers 6 and 11 occupy the illustrated positions, actuation thereof to the opposite operative positions may be effected by throwing the master reversing switch 7a to the position Rev. Similar control of the main reversers 6 and 11 may be effected through the use of the master reversing 110 switch 12a on vehicle 2. Consequently, both forward and reverse operation of the driving motors may be obtained from either operating platform of the train by means of two small-capacity conductors, respectively 115 corresponding to the forward and the reverse actuating coils of the main reversers 6 and 11. By employing this construction, the seven main-circuit cables that would otherwise be necessary to effect reversing control 120 125 130

of the two motors are obviated in favor of two small capacity jumper cables or train lines.

It will be noted that, in accordance with 5 customary practice, the conductor 52 is crossed with the other auxiliary-circuit or train-line conductor in passing from the one vehicle to the other, whereby correct forward and reverse operation may be effected 10 with identically-operated master reversing switches upon the two operating platforms.

Assuming that the "K" controller 3 is now thrown to its first operative position *a*, a circuit is established from the Trolley through 15 conductors 55, 62 and 63, control fingers 16 and 17, which are bridged by contact segment 64 of the controller, conductor 65, the entire accelerating resistor 4, conductor 66, control fingers 19 and 20, which are bridged by 20 contact segment 67 of the controller 3, conductor 68, control fingers 69 and 70, which are bridged by contact segment 71 of the auxiliary reversing switch 7 in its forward position, conductor 72, armature A1, conductor 73, contact segment 74 of the main reverser 6, conductor 75, field winding F1, conductor 76, contact segment 77 of the main reverser 6, conductor 78, control fingers 79 and 80, which are bridged by contact segment 30 30a of the auxiliary reversing switch 7, conductor 81, the entire accelerating resistor 5, conductor 82, control fingers 23 and 24, which are bridged by contact segment 83 of the "K" controller, conductors 84, 85 and 86, 35 terminal board 87 of the vehicle 1, jumper cable or train line 27 between vehicles, terminal board 88 of the vehicle 2, conductor 89, junction-point 90, conductor 91, control fingers 92 and 93, which are bridged by contact segment 94 in the normal or "off" position of the auxiliary reversing switch 12, conductor 95, armature A2, conductor 96, contact segment 97 of the main reverser 11, conductor 98, field winding F2, conductor 40 45 99, contact segment 100 of the main reverser 11, conductor 101, control fingers 102 and 103, which are bridged by contact segment 104 of the auxiliary reversing switch 12, and conductor 105 to Ground. The two sets of 50 driving motors are thus connected in series relation with the accelerating resistors 4 and 5, as previously explained in connection with Fig. 1.

By actuating the "K" controller 3 through 55 its successive operative positions *b* to *e*, inclusive, control fingers 110 to 113, inclusive, successively engage the corresponding contact segments 83 and 67, whereby the accelerating resistors 4 and 5 are gradually removed 60 from circuit, as will be understood, to provide a desirably smooth acceleration of the motors to full-series relation. In the full-series position *e*, therefore, control finger 113, which is connected to conductor 62, 65 makes direct connection with control finger

20 through contact segment 67, thus short-circuiting the accelerating resistor 4, while control fingers 110 and 24 are directly connected, through contact segment 83, to short-circuit the accelerating resistor 5. 70

Assuming now that the motors are to be operated from the other platform, that the vehicle 2 is to be the leading vehicle and that the motors are connected in initial parallel relation corresponding to position *f* of the "K" controller 8, the various circuits may be traced as follows. In the first place, the reversing switches 12 and 12a will have been thrown, by their common operating handle, to the position marked "For.", which, 80 while corresponding to forward operation of the vehicle 2, corresponds of course, to the reverse direction of operation from that assumed when the vehicle 1 was leading. In other words, the actuating coils Rev.-1 of 85 the main reverser 6 and Rev.-2 of the main reverser 11 are, in this case, energized to throw the main reversers to the position marked "Rev.".

Under the conditions noted, therefore, a 90 circuit is established from the Trolley through conductors 115 and 116, control fingers 36 and 37, which are bridged by contact segment 117 in position *f* of the "K" controller 8, whence circuit is continued 95 through conductor 118, control fingers 119 and 93, which are bridged by contact segment 120 of the auxiliary reversing switch 12, conductor 95, armature A2, conductor 96, contact segment 121 of the main reverser 100 11 in its reversed position, conductor 99, field winding F2, conductor 98, contact segment 122, conductor 123 and contact segment 124 of the main reverser 11, conductor 101, control fingers 102 and 125, which are 105 bridged by contact segment 126 of the auxiliary reversing switch 12, conductor 127, the entire accelerating resistor 10, conductor 128, control fingers 41 and 42, which are bridged by contact segment 129 of the "K" 110 controller 8, and conductor 44 to Ground.

A branch circuit is continued from the contact segment 117 of the "K" controller through control finger 45, conductor 130, a portion of the accelerating resistor 9, conductor 131, control fingers 46 and 47, which are bridged by contact segment 132 of the controller 8, conductors 133 and 89, terminal board 88, jumper cable or train line 27, terminal board 87, conductors 86 and 134, control fingers 135 and 70, which are bridged by contact segment 136 in the normal or "off" position of the auxiliary reversing switch 12, conductor 72, armature A1, conductor 73, contact segment 137 of the main reverser 6, conductor 76, field winding F1, conductor 75, contact segment 138, conductor 139 and contact segment 140 of the main reverser 6, conductor 78, control fingers 80 and 141, which are bridged by contact seg- 120 125 130

ment 142 of the auxiliary reversing switch 7 and conductor 143 to Ground. In this way, the two sets of driving motors are connected in parallel relation with substantially equal values of resistance inserted in circuit therewith, as previously explained in connection with Fig. 1.

By actuating the controller 8 through its successive positions g' and h' , the resistors 10 9 and 10 are gradually excluded from circuit, as will be understood, to effect acceleration of the motors to full-parallel relation.

In addition to the saving in the number of 15 cables or train lines necessary between the vehicles that is effected by the use of double-capacity resistors and remotely-controlled reversers, as previously set forth, a further reduction in the number of train lines is 20 effected in our invention by the use of the auxiliary reversing switches 7 and 12, which are employed in an active position on the leading vehicle and in the normal or "off" position on the trailing vehicle, in each case. Consequently, by the various expedients set 25 forth, complete series-parallel and reversing control of a plurality of power units on tandem-connected vehicles from operating platforms at each end of the train may be effected through the use of only one main- 30 circuit conductor and two auxiliary-circuit or small-capacity conductors. Furthermore, no additional switching devices or additional manipulation or thought on the part 35 of the train operator is necessary since, upon leaving one platform, after returning the "K" controller 3 to its "off" position and stopping the vehicle, he merely removes his reverser handle, which necessitates actuating the reversing switches 7 and 7a to the 40 "off" position, in accordance with the familiar handle interlock that is standard in all "K" control equipments, and then proceeds to the other operating platform, throws the reversing switches to the forward 45 or the reverse operative position and actuates the "K" controller proper in the usual way.

While we have illustrated our invention 50 in connection with a single driving motor upon each vehicle, it will be understood that equipments embodying two permanently parallel-connected motors upon each vehicle, as well as other driving-unit arrangements, may utilize the principles of the present 55 invention to advantage. Consequently, we do not wish to be restricted to the specific circuit connections or arrangement of parts herein set forth, as various modifications thereof may be made without departing 60 from the spirit and scope of the invention. We desire, therefore, that only such limitations shall be imposed upon our invention as are indicated in the appended claims.

We claim as our invention:

65 1. A system of train-control for a plural-

ity of vehicles comprising a driving motor on each vehicle, and means for effecting series-parallel operation and reversal of said motors, said means embodying a single train-line conductor carrying motor current and a 70 plurality of relatively small-capacity conductors.

2. A system of train-control for two tandem-connected vehicles comprising a driving motor on each vehicle, and means for effecting series-parallel operation and reversal of said motors from each end of the train, said means embodying a single train-line conductor carrying motor current for effecting the series-parallel control and two auxiliary-circuit train-line conductors for effecting the 75 reversing control.

3. A system of control comprising a plurality of power units, reversing controllers therefor, control means corresponding to the 80 respective units, and means movable with said controllers for connecting the one or the other power unit directly in circuit with the remaining power unit and the corresponding control means.

4. A system of control comprising a plurality of power units, reversing controllers therefor, a plurality of accelerating resistors corresponding to the respective units, and means actuated by said controllers for connecting the one or the other power unit directly in circuit with the remaining power unit and the corresponding resistor.

5. A system of train control for a plurality of vehicles comprising a driving motor on each vehicle, reversing controllers therefor, control means corresponding to each motor, a supply-circuit conductor on each vehicle and a conductor between vehicles, and means movable with said controllers for connecting the corresponding motor either directly in circuit between said conductors or in circuit with the corresponding control means.

6. A system of train control for a plurality of vehicles comprising a driving motor on each vehicle, master reversing controllers therefor, a plurality of accelerating resistors corresponding to the respective motors, a grounded conductor on each vehicle and a conductor between vehicles, and switching means actuated by said controllers for connecting the corresponding motor either directly in circuit between said conductors and with the other motor and resistor or in circuit with the corresponding resistor and the other motor.

7. A system of train control for a plurality of vehicles comprising a driving motor on each vehicle, master reversing controllers therefor, a plurality of accelerating resistors corresponding to the respective motors, a grounded conductor on each vehicle and a conductor between vehicles, and switching means actuated by said controllers for connecting the corresponding motor either di- 125 130

rectly in circuit between said conductors and with the other motor and resistor when the corresponding controller occupies its "off" position or in circuit with the corresponding resistor and the other motor when the corresponding controller occupies an operative position.

8. A system of control comprising a plurality of driving motors, reversing controllers therefor, control means for the respective motors, and switching means for con-

necting a motor directly in circuit with the one or the other control means in accordance with the occupation of an operative or an inoperative position by the corresponding controller.

In testimony whereof, we have hereunto subscribed our names this 4th day of October, 1919, and the 24th day of November, 1919, respectively.

WILLIAM G. BROOKS.
LYNN G. RILEY.
